(57) **CLAIM**

The ornamental design for a transparent container with multi-colored food product, as shown and described.

DESCRIPTION

FIG. 1 is a top plan view of the transparent container with multi-colored food product showing my design;

FIG. 2 is a left side elevation view thereof;

FIG. 3 is a front elevation view thereof;

FIG. 4 is a right side elevation view thereof; and,

FIG. 5 shows a bottom plan view thereof.

The contrast of shading shown in the drawing indicates the differently colored food product creating a pattern.
